(57) **CLAIM**

The ornamental design for a recycling receptacle, as shown and described.

DESCRIPTION

FIG. 1 is a perspective view of a first embodiment of the recycling receptacle of the present invention;

FIG. 2 is a front elevation view thereof;

FIG. 3 is a right side elevation view thereof, the left side elevation view being a mirror image thereof;

FIG. 4 is a rear elevation view thereof;

FIG. 5 is a top plan view thereof;

FIG. 6 is a bottom plan view thereof;

FIG. 7 is a perspective view of a second embodiment;

FIG. 8 is a front elevation view thereof;

FIG. 9 is a right side elevation view thereof, the left side elevation being a mirror image thereof;

FIG. 10 is a rear elevation view thereof;

FIG. 11 is a top plan view thereof;

FIG. 12 is a bottom plan view thereof;

FIG. 13 is a perspective view of a third embodiment;

FIG. 14 is a front elevation view thereof;

FIG. 15 is a right side elevation view thereof, the left side elevation view being a mirror image thereof;

FIG. 16 is a rear elevation view thereof;

FIG. 17 is a top plan view thereof;

FIG. 18 is a bottom plan view thereof;

FIG. 19 is a perspective view of a fourth embodiment;

FIG. 20 is a front elevation view thereof;

FIG. 21 is a right side elevation view thereof, the left side elevation being a mirror image of FIG. 3;

FIG. 22 is a rear elevation view thereof;

FIG. 23 is a top plan view thereof;

FIG. 24 is a bottom plan view thereof;

FIG. 25 is a perspective view of a fifth embodiment;

FIG. 26 is a front elevation view thereof;

FIG. 27 is a right side elevation view thereof, the left side elevation being a mirror image of FIG. 3;

FIG. 28 is a rear elevation view thereof;

FIG. 29 is a top plan view thereof; and,

FIG. 30 is a bottom plan view thereof.
